UNITED STATES PATENT OFFICE

2,468,551

SNAP ACTION ELECTRIC SWITCH

Robert W. Goff, Schenectady, N. Y., assignor to
 General Electric Company, a corporation of
 New York

Application October 24, 1946, Serial No. 705,358

7 Claims. (Cl. 74—100)

1

My invention relates to snap action devices, and more particularly to snap action electric switches of the latched in type.

The invention has particular application to double throw limit switches of the snap action type having a switch actuating rocker arm alternately latched in one of two predetermined angularly spaced circuit controlling positions, in combination with means for disengaging the latches and simultaneously storing energy in an actuating spring to move the rocker arm with a snap action.

The invention has for its principal object the provision of a new and improved limit switch of the above character which shall be simple in construction, inexpensive and economical to manufacture, reliable in operation, and characterized by a greatly improved operating life.

My invention itself, together with further objects and advantages thereof, may be fully appreciated by referring now to the following detailed specification taken in conjunction with the accompanying drawings, in which Fig. 1 is a front elevational view of a snap acting limit switch embodying my invention; Fig. 2 is a cross-sectional view taken along the line 2—2 of Fig. 1 looking in the direction of the arrows; Fig. 3 is a fragmentary view of the switch actuating mechanism shown at Fig. 1, certain parts being shown in section in the manner indicated by the line 3—3 of Fig. 2; Fig. 4 is a fragmentary cross-sectional view taken along the line 4—4 of Fig. 2; Fig. 5 is a rear elevational view of the switch shown at Fig. 1; Fig. 6 is a cross-sectional view taken along the line 6—6 of Fig. 5, looking in the direction of the arrows; and Fig. 7 is a detailed view of the switch arm shown at Figs. 5 and 6. The distinctively new and novel features which characterize the invention, together with the scope of the invention, will be pointed out with particularity in the claims appended to this application.

Referring now to the drawings, and particularly to Fig. 1, I have shown an electric limit switch mounted within a casing 1 having an internal dividing wall 2 and provided upon opposite sides thereof with covers 3 and 4 to provide separate compartments 5 and 6 for the switch operating mechanism and the switch contact mechanism, respectively. The switch compartment 6 is provided with a tapped conduit connection 8 for the entrance of suitable conducting lead wires. The casing cover 3 for the operating mechanism compartment 5 is shown formed of metal, while the casing 4 for the switch compartment 6 is formed of a suitable insulating material,

2

such as a molded insulating compound or the like.

By way of illustration of the invention, I have shown a pair of double-pole double-throw limit switches actuated by a common switch arm 9.

5 The switch arm 9, shown best at Figs. 2, 5, 6, and 7, is mounted upon one end of a rocker shaft 10 journaled in the dividing wall 2 and carrying at its other end a rocker arm 11. The rocker arm 11 and the switch arm 9, together with the connecting rocker shaft 10, form a unitary switch member actuatable by the switch operating mechanism.

As shown particularly at Figs. 5 and 6, each double-pole double-throw limit switch in the 15 compartment 6 comprises two spaced pairs of switch contacts 12 and 13, and movable bridging contact members 14. The bridging contacts 14 are slidably mounted upon a rectangular supporting bar 15 and are resiliently biased to a central position within a slidable yoke 16 by a pair of helical compression springs 17 positioned between the contact members 14 and the parallel sides of the yoke. As clearly shown at Fig. 6, the yoke 16 is slidably mounted upon the contact supporting

20 bar 15. For the purpose of sliding the yoke 16 longitudinally of the bar 15, thereby to move the bridging contacts 14, I have provided on each yoke a pin 18 extending rearwardly from the bight of the yoke 16 into one of a pair of slots 19 formed 25 at opposite ends of the pivotally mounted switch arm 9 (see particularly Fig. 7).

The switch operating mechanism will be best 30 understood by referring now particularly to Figs. 1, 2, 3 and 4. As hereinbefore described, the

35 rocker arm 11 mounted upon one end of the rocker shaft 10 extends into the compartment 5 housing the operating mechanism. From Figs. 1 and 3 it will be observed that a pair of latch levers 20 and 21 are pivotally mounted in the base

40 at points 22 and 23, respectively, and are biased into engagement with opposite ends of the rocker arm 11 by means of associated helical compression springs 24 and 25, respectively. The springs 24 and 25 are seated in recesses in the latch levers

45 20 and 21, respectively, and bear against abutments 26 and 27, respectively. The abutments are formed on opposite sides of the casing 1 adjacent the latch levers and serve as limiting stops in the latch disengaging movement of the associated latch members.

50 Each latch lever 20 and 21 is provided with a latching shoulder 28 with which the opposite ends of the rocker arm 11 are alternately engageable. Each latch lever is also provided with a limit stop shoulder 29 with which the opposite ends of the

rocker arm 11 are also alternately engageable in inverse relation with respect to the latch shoulders 28. That is, when the latch shoulder 28 on the latch lever 20 is in engagement with one end of the rocker arm 11, the stop shoulder 29 of the other latch lever 21 is in engagement with the opposite end of the rocker arm 11, as shown at Figs. 1 and 3. Conversely, the latch shoulder 28 of the lever 21 and the stop shoulder 29 of the lever 20 will be simultaneously effective when the rocker arm 11 is in its other circuit controlling position. This latching mechanism including the limit stop shoulder 29 is more particularly described and claimed in my Patent 2,390,365, issued December 4, 1945.

The rocker arm 28 is actuated with a snap action between two angularly spaced limiting circuit controlling positions by means of a pair of oppositely reciprocable arms 30 and 31 movable substantially transversely of the rocker arm 11 and in opposite directions, alternately to disengage the engaged latching shoulder 28 on the operative latch lever 20 or 21 and simultaneously to store energy in an actuating spring for moving the rocker arm 11 when the latch shoulder is released. As shown more particularly at Fig. 2, each of the reciprocable arms 30 and 31 is formed of a pair of plates 32 and 33 connected together in parallel spaced relation by a pair of transverse blocks 34 and 35. The arms 30 and 31 for the greater part of their length are disposed in substantially parallel spaced relation, but at their upper ends the arms 30 and 31 are bent outwardly away from the center line of the switch. The reciprocable arms 30 and 31 are pivotally mounted at their upper ends upon pivot pins 36 and 37, respectively, which are carried at opposite ends of a centrally pivoted operating arm 38. The operating member 38 is pivotally mounted at its center upon the base 1 for limited rocking movement.

The spacing blocks 34 and 35 forming part of the reciprocable arms 30 and 31 are spaced apart longitudinally of the arms and are apertured to support loosely between the plates 32 and 33 a pair of actuating pins 39 and 40, the pin 39 being slidably mounted in the arm 30 and the pin 40 being slidably mounted in the arm 31. The spacing blocks 35 receive the pins 39 and 40 in laterally elongated slots 35a so that the pins 39 and 40 are loosely mounted within the arms 30 and 31 for limited lateral lost motion with respect to the arms. Moreover, the actuating pins 39 and 40 are reciprocable within the arms 30 and 31 and are arranged for alternate spring press engagement with opposite ends of the rocker arm 11 upon downward actuating movement of the associated arms 30 or 31. For this purpose, each actuating pin 39 and 40 is provided with a collar 41. The collars 41 serve as seats for a pair of actuating springs 42 and 43 interposed between the collars 41 and the spacing blocks 34 in the reciprocable arms 30 and 31, respectively. As illustrated particularly at Figs. 1 and 3, the surface of the rocker arm 11 in the regions of engagement with the actuating pins 39 and 40 is cylindrically dished, as at 11a and 11b, for a purpose which will be more fully described hereinafter.

The outer plates 32 of the reciprocable arms 30 and 31 are longer than the inner plates 33 and extend below the rocker arm 11 into camming engagement with a cam roller 44 rotatably mounted upon the base 1. For this purpose the depending ends of the reciprocable arms 30 and

31 are provided with sloped camming surfaces 45 and 46, respectively.

The centrally pivoted operating arm 38 is biased to one of two angularly spaced terminal positions by a compression spring 47 interposed between one end of the operating member 38 and the adjacent abutment 26 on the casing 1. Obviously, the operating member 38 may be biased to either position simply by locating the biasing spring 47 either upon the abutment 26 or upon the abutment 21. The operating member 38 is moved about its pivot against the bias of the spring 47 by a reciprocable push rod 48 extending through the upper portion of the switch casing 1 into engagement with an upwardly extending arm 49 on the operating member. Connection between the arm 49 and the push rod 48 is made by a pin 50 which extends from the upper end of the arm 49 into an elongated slot 51 in the push rod 48. The pin 50 is normally held centered in the slot 51 by a pair of opposing compression springs 52 within the push rod 48, the compression springs and the slot 51 providing a limited amount of overtravel of the push rod 48 with respect to the pin 50 and the operating member 38.

With the foregoing detailed description of the various parts of my switch mechanism and their manner of organization, it is believed that the mode of operation of the device will be evident from the following brief description.

Assuming that initially the mechanism is in the position shown in the drawings, and referring particularly to Figs. 1 and 3, movement of the bridging contacts 14 from the position shown at Fig. 5 into engagement with the contacts 13 is effected by movement of the push rod 48 from the position shown in solid lines at Fig. 1 to the dotted position shown at Fig. 1. More specifically, when the push rod 48 is moved to the left, as viewed at Fig. 1, the operating member 38 is rotated in a counterclockwise direction about its pivot point against the bias of the spring 47. Rotary movement of the centrally pivoted operating member 38 effects opposite longitudinal sliding movement of the reciprocable cam follower arms 30 and 31, the arm 30 moving downwardly and the arm 31 moving upwardly as viewed in Figs. 1 and 3.

As the arm 30 moves downwardly, it is also forced laterally outward by action of the cam surface 45 in moving over the cam roller 44. This outward movement of the arm 30 brings the spacing block 35 on this arm into engagement with the operative latch lever 20, thereby to effect disengagement of the latch shoulder 28 on the lever 20 with the end of the rocker arm 20. Simultaneously, the downward longitudinal movement of the reciprocable arm 30 brings the actuating pin 39 into engagement with the dished portion 11a of the rocker arm 11. The rocker arm 11, however, cannot move until the latch shoulder 28 on the latch lever 20 is actually disengaged. Prior to such disengagement, the actuating spring 42 is compressed, thereby to store energy for moving the actuating pin 39 and the rocker arm 11 as soon as the latch lever 20 is disengaged.

During this downward and laterally outward movement of the arm 30, the actuating pin 39 remains in fixed engagement with one point of the rocker arm 11 by reason of the elongated slot 35a which provides lateral lost motion between the actuating pin 39 and the arm 30. In this connection, it should be noted that, were this lost motion not provided, the pin 39 would be forced to slide outwardly along the rocker arm

as the reciprocable arm 30 is moved downward and outward. Such forced sliding would cause binding of the pin 39 against one side of the slot in the spacing block 35 and the resultant friction would result in lost power, if not uncertain operation, in the movement of the rocker arm 11. Thus, as the arm 30 is moved downwardly and outwardly, the spacing block 35 is also moved outwardly so that, at the moment of latch release, the pin 39 is on the inner side of the elongated slot 35a.

As soon as the latch shoulder 28 of the latch lever 20 is released, the spring 42 presses the pin 39 downwardly, thereby to rotate the rocker arm 11 into engagement with the stop shoulder 29 on the latch lever 20 and to bring the opposite end of the rocker arm 11 into engagement with the latch shoulder 28 on the latch lever 21. With this rocker arm in this position, the latch lever 21 becomes effective by reason of its biasing spring 25. The actuating pin 39, then, assumes the position of the actuating pin 40 as viewed at Fig. 3, that is, the pin 39 then engages the low side of the rocker arm 11.

It will now be evident from Fig. 3 that the actuating pin which engages the low side of the rocker arm 11 moves to the outside of the elongated slot 35a by reason of the force of the actuating spring and the slope of the dished rocker arm surface 11a or 11b. In Fig. 3 the actuating pin 40 is shown in this position. Thus, to continue with the foregoing operation, it will be further evident that, after the actuating pin 39 is released to rotate the rocker arm 11, the pin moves from the inside of the elongated slot to the outside. The pin remains in this position with respect to the slot upon reverse actuation, so that upon initiation of actuating movement of either pin, the pin begins its movement in the outside of the elongated slot 35a as illustrated by the pin 39 in Fig. 3. This will be evident from following the action of the pin 40 in the arm 31 as the pin 39 in the arm 30 is moved downwardly. During such movement, the arm 31 is moved upwardly, and the pin 40 is withdrawn from engagement with the rocker arm 11. Such withdrawal leaves the pin 40 in the outside of the slot 35a, as shown at Fig. 3. During such withdrawing movement of the inactive actuating pin, the associated reciprocable arm 31 is held in following engagement with the cam roller 44 by the latch lever 21 and the latch biasing spring 25.

It will now be evident from the foregoing description of the operation that a particular feature of my invention is the loose or lateral lost motion mounting of the actuating pins 39 and 40 in the reciprocable arms 30 and 31, in combination with the cylindrically dished surfaces 11a and 11b in the rocker arm 11. These constructional features prevent binding of the actuating pins against the sides of the spacing block 35a during actuating movement of the mechanism.

While I have shown but one preferred embodiment of my invention by way of illustration, many modifications will occur to those skilled in the art and I, therefore, wish to have it understood that I intend in the appended claims to cover all such modifications as fall within the true spirit and scope of my invention.

What I claim as new and desire to secure by Letters Patent of the United States is:

1. A snap acting device comprising a rocker arm pivotally mounted intermediate its ends for movement between angularly spaced terminal

positions, a pair of latch means arranged alternately to engage opposite ends of said rocker arm selectively to retain said arm in either of said positions, a pair of movable latch releasing members alternately operable to release said latch means, and a pair of actuating members resiliently mounted on said latch releasing members and arranged alternatively to engage opposite ends of said rocker arm to move said rocker arm between said positions with a snap action upon release of the engaged latch means.

2. A snap acting device comprising a rocker arm pivotally mounted intermediate its ends for movement between angularly spaced terminal positions, a pair of latch levers including means arranged alternately to engage opposite ends of said rocker arm selectively to retain said arm in either of said positions, a pair of movable latch releasing members alternately operable to release said latch means, a pair of actuating pins slidably mounted on said latch releasing members, respectively, and arranged alternatively to engage opposite ends of said rocker arm, and spring means interposed between said latch releasing members and said actuating pins and alternately operable to press said pins into engagement with said rocker arm thereby to move said rocker arm between said positions with a snap action upon release of the engaged latch means.

3. A snap acting device comprising a rocker arm pivotally mounted for movement between angularly spaced terminal positions, a pair of latch members including means alternately engageable with opposite ends of said rocker arms selectively to retain said arm in either of said positions, a pair of reciprocable members oppositely movable substantially transversely of said rocker arm, a pair of spring pressed actuating members carried by said reciprocable members and alternately engageable with opposite ends of said rocker arm to move said arm between said positions, and cam means operable upon actuating movement of said reciprocable members simultaneously to effect latch releasing lateral movement of the operative reciprocal member.

4. A snap acting device comprising a rocker arm pivotally mounted for movement between angularly spaced terminal positions, a pair of latch members including means alternately engageable with opposite ends of said rocker arm selectively to retain said arm in either of said positions, a pair of reciprocable members oppositely movable substantially transversely of said rocker arm, a pair of spring pressed actuating pins loosely mounted upon said reciprocable members and positioned alternately to engage opposite ends of said rocker arm to move said rocker arm between said positions, the surface of said rocker arm at points of engagement with said actuating pins being of cylindrical dished formation, and camming means operable upon actuating movement of said reciprocable members simultaneously to effect latch releasing lateral movement of the operative reciprocating member.

5. A snap acting device comprising a rocker arm pivotally mounted for movement between angularly spaced terminal positions, a pair of latch members including means alternately engageable with opposite ends of said rocker arm selectively to retain said arm in either of said positions, a pair of reciprocable cam follower arms oppositely movable substantially transversely of said rocker arm, a pair of spring pressed

actuating pins slidably mounted upon said cam follower arms, lost motion means providing limited lateral displacement of said pins with respect to said arms, said rocker arm being cylindrically dished in the regions of engagement with said pins, and camming means engageable with said cam follower arms upon actuating movement of said arms simultaneously to effect latch releasing lateral movement of the operative follower arm.

6. A snap-acting device comprising a rocker arm pivotally mounted for movement between angularly spaced terminal positions, a pair of latch members including means alternately engageable with opposite ends of said rocker arm selectively to retain said arm in either of said positions, a pair of reciprocable cam follower arms oppositely movable substantially transversely of said rocker arm, a pair of spring pressed actuating pins slidably mounted upon said cam follower arms, lost motion means providing limited lateral movement of said pins with respect to said arms, and camming means engageable with said cam follower arms upon actuating movement of said arms simultaneously to effect latch releasing lateral movement of the operative follower arm.

7. A snap acting device comprising a rocker arm pivotally mounted intermediate its ends for movement between angularly spaced terminal positions, a pair of latch levers disposed substantially perpendicularly to said rocker arm and pivotally mounted for movement toward and away from opposite ends of said rocker arm, said latch levers including latching shoulders ar-

5 ranged alternately to retain said rocker arm in either of said terminal positions, a pair of reciprocable cam follower arms disposed in substantially parallel spaced relation intermediate, said latch levers and substantially transversely of said rocker arm, an operating member connected simultaneously to slide said cam follower arms transversely of said rocker arm in opposite directions, a spring pressed actuating pin mounted upon each of said cam follower arms

10 for longitudinal sliding and limited transverse movement with respect thereto, said actuating pins being positioned for engagement with opposite ends of said rocker arm, and camming means engageable with said cam follower arms upon actuating movement of said arms simultaneously to move said follower arms transversely in the same direction, the operative follower arm by said transverse movement engaging and releasing the operative latch lever, thereby to permit the associated spring pressed actuating pin to move said rocker arm between said terminal positions with a snap action.
